DRILLING JOINT

Cicero C. Brown, Houston, Tex.

Application March 21, 1947, Serial No. 736,359

4 Claims. (Cl. 255—28)

1

This invention relates to improvements in apparatus for rotary drilling of well bores and refers more particularly to telescope joints adapted to be interposed in a drill stem.

This application is related to my co-pending application, Serial No. 632,927, filed December 5, 1945. The device of this invention provides an improved means for controlling the weight applied to the drill bit, localizes the neutral point in the drill stem, and prolongs the life of the drill stem by absorbing or damping out vibrations and other shocks imparted to the drill stem during operations.

Heretofore in devices of this character the relatively movable splines or other non-circular connections between the telescoping members have been exposed to the abrasive matter of the well drilling fluid. This abrasive matter materially reduces the life of the device and often times interferes with its intended operation. The use of rubber or rubber like material in the splined inner connection has been recommended and has certain advantages in that the drilling fluid serves as a lubricant and the abrasive matter does not have the same wearing effect upon the resilient material of this type spline. However, this type connection has not proved entirely satisfactory for all purposes due to the inherent weakness of this material in the transmission of the heavy loads often encountered in drilling deep well bores.

An object of this invention is to provide a drill stem telescope joint in which the working parts of the telescope members are housed in a sealed chamber and thus protected from abrasive materials.

Another object is to provide a drill stem telescope joint in which the relatively movable, torque transmitting parts between the telescope members are housed in a sealed chamber filled with a lubricant.

A further object is to provide a drill stem telescope joint in which the torque transmitting relatively movable parts between the telescoping members are housed in a sealed chamber which may be filled with hydraulic material whereby likelihood of collapse of the outer member is reduced.

Still another object is to provide a tool of the character described wherein the relatively slideable torque transmitting parts may be constructed of rigid wear-resisting material and shielded from abrasive foreign matter.

Other and further objects will appear from the following description.

2

In the accompanying drawings which constitute a part of the instant specification and are to be read in conjunction therewith, and wherein like reference numerals designate like parts of the various views:

Fig. 1 is a schematic sectional view of a well bore showing in elevation a drill stem and tools equipped with a device embodying this invention;

Fig. 2 is a vertical sectional view of the upper portion of the device shown in Fig. 1;

Fig. 3 is a vertical sectional view of the lower portion of the device shown in Fig. 1; and

Fig. 4 is a view taken along the line 4—4 in Fig. 3 in the direction of the arrows.

Referring to the drawings, more particularly Fig. 1, the well bore is shown schematically at 10. Joints 11 of the drill stem are suspended from the surface in a manner well known to those skilled in the art and have interposed therein the device of this invention. The drill bit 12 is attached by a suitable drill collar 13 to the lower end of the telescope joint. In actual operation a suitable number of drill collars will be used to give the desired weight at the bottom 25 of the hole. A selected drilling weight can by this manner be located below the telescope joint, thus maintaining a uniform load upon the bit.

With regard to the drill stem telescope joint, it may be considered that the device comprises in general two telescoping members. The outer of the members includes a coupling sleeve 14 which has threaded connection with the lowermost drill stem joint 11. Sleeve 14 has an enlarged bore 14a which provides a recess for housing the lip type packing ring 15. The packing ring may be made of any suitable resilient material such as rubber, neoprene or other synthetics.

At its lower end coupling sleeve 14 threadedly receives a tubular sleeve 16. The upper end of tube 16 is threadedly connected to a packing carrier 17 which carries seal member 15. The internal bore 16a of the tubular sleeve provides a smooth cylindrical surface of uniform diameter to cooperate with sealing means carried by the inner telescoping member as will be hereinafter more fully described. A bore 16b is provided in sleeve 16 leading into the upper end of the interior of sleeve 16 to maintain the proper pressure differential across seal member 15.

The lower end of sleeve 16 is threadedly connected to spline carrier 18. The spline carrier is provided with a valved opening 18a. This valved opening provides a means for forcing a hydraulic or lubricating material into the space between 45 the telescoping members with the tool assembled.

The lower end of sleeve 16 is threadedly connected to spline carrier 18. The spline carrier is provided with a valved opening 18a. This valved opening provides a means for forcing a hydraulic or lubricating material into the space between 55 the telescoping members with the tool assembled.

The spline carrier has integrally formed splines 18b on its internal surface.

The spline carrier is threaded at its lower end to tubular sleeve 19 which constitutes the lower portion of the outer telescope member. Sleeve 19 is provided with an elongated bore of uniform diameter which provides a sealing surface for sliding seal members as will be hereinafter more fully described.

It is important to note that buttress type threads are provided for the connections between the component parts of the outer tubular member. By using these buttress type threads the parts of the outer member may be constructed of somewhat narrower gauge. It is of course understood that in drilling operations the maximum outside diameter of the joints of a drill stem must be kept low in the interest of economy.

The inner telescope member comprises the coupling member 20, mandrel 21 and sealing or flow tube 22. The coupling 20 provides an attachment for the lower end of the device with the drill collar 13. In addition the shoulder 20a of the coupling engages the lower end of sleeve 19 providing a stop for telescoping movement of the inner and outer members.

The mandrel 21 intermediate its ends is provided with elongated external splines 21a. These splines mate with splines 18b of the outer member. Preferably the splines are the buttress type. The buttress type splines are of V-shape but have one side inclined with respect to a radius through its apex and the other side extending along a radius. This arrangement provides an enlarged driving surface between the spline members. In addition, the arrangement provides a shear area for each spline which is equivalent to the entire base of the spline, and the total shear area for all of the splines on either element is equal to the length of these splines times the entire circumference of the respective elements at the bases of the splines. Furthermore, the driving surfaces are kept at a sufficiently great angle with respect to the direction of application of driving force on each spline to reduce the likelihood of their sticking. This angle also facilitates a relatively easy sliding movement between the surfaces even while under torque load. Throughout this specification this type spline will be referred to as buttress type splines.

In order to provide a sealed chamber for the working parts or splined connection between the members, seals are provided between the telescope members adjacent the ends of the elongated splines 21a. At the lower end the mandrel has a portion 21b having substantially the same outside diameter as the inside diameter of tubular sleeve 19. Sliding seal means are provided between the portion 21b and sleeve 19. Preferably these seals are of the O-ring groove assembly type. A groove is provided in the outer periphery of portion 21b. O-ring 23 fits loosely within the groove and normally has sufficient outside diameter to frictionally engage the internal wall of sleeve 19. In as much as portion 21b is enlarged, the groove does not weaken the mandrel.

A similar seal is provided at the top end of the elongated splines 21. To facilitate assembly of the tool this is accomplished by means of a seal carrier ring 24 threaded to the upper end of mandrel 21. Again the seal is preferably formed by use of an O-ring groove assembly. A groove is provided in the outer periphery of ring 24 and loosely receives O-ring 25. This O-ring normally

has sufficient outside diameter to frictionally engage the internal wall of tubular sleeve 16. Preferably ring 24 has a close tolerance with the inner surface of sleeve 16.

It is important that with the telescoping members in their extreme telescoped position the lower end of sleeve 19 abuts shoulder 20a of coupling 20. Thus, in this position, the splines of the splined connection are protected against distortion from a jar, as the splines themselves do not form the means of stopping or limiting telescoping movement of the members. In this respect, the splines are likewise protected from distortion by shoulders 24a of the seal carrier and shoulder 18c of the spline carrier. These shoulders engage and serve as stops limiting extension of the telescoping members.

The sealing or flow tube 22 is threaded to mandrel 21 and extends upwardly into the lower drill stem joint 11. The length of tube 22 must be sufficient to provide a sealing surface cooperable with lip seal 15 when the inner and outer telescoping members are in their extreme extended position. This arrangement is such that an auxiliary seal is provided against flow of drilling fluid between the two telescoping members. Nevertheless, when the members are in their extended position and are forced to their telescope position fluid within the space formed between flow tube 22 and the outer member may readily flow past the lip type seal member 15 when the pressure beneath the seal is greater than that above the seal. The tube provides a flow passage for drilling fluid from the lower most joint 11 to the mandrel.

While the sealing assemblies, including O-rings 23 and 25, seal off the chamber which houses the splined connection protecting the relative sliding parts from abrasive material this protection may be made more positive by filling this chamber with a light lubricating oil or the like. Valved opening 18a provides a means for accomplishing this. Preferably this hydraulic material is forced into the chamber under pressure which will be substantially that encountered in drilling operations. This material serves a four fold purpose. It reduces the likelihood of abrasive or other foreign matter seeping past the seal assemblies, protects sleeves 16 and 19 from excessive hydrostatic pressures, lubricates the splined connection and serves as a dash-pot to absorb or dampen vibrations and other shocks to which the drill stem is subjected in drilling operations.

Preferably, when the lubricant bath is provided for the splines, one of the splines 21a is truncated throughout most of its length as shown at 26 in Figs. 2 and 4. By this expedient the dash-pot effect, due to restricted flow of the lubricant past the spline engagement is reduced throughout most of the stroke or relative movement of the members whereby they move relatively freely and at the same time there is provided a damping of excessive shocks, vibrations and the like. As the entire length of the spline is not ground off relative longitudinal movement of the splines is much slower when the inner and outer members are completely telescoped.

It is believed that the operation of this invention is obvious from the foregoing description. The tool is interposed in a pipe string usually between the lower-most drill stem joint and the upper-most drill collar. However, it is often desirable to interpose drill collars above the telescope joint as this sometimes facilitates drilling of a straight hole as will be understood

by those skilled in the art. Tools are lowered into the well bore until bit 12 engages the bottom of the bore. Sufficient weight is placed upon the drill stem to telescope the inner and outer members of the telescope joint, rotary slips are set and the tools rotated.

As the bit bores into the formations the drill stem and outer member of the telescope joint remain at a substantially constant level. However, the inner member of the telescope joint moves downwardly reflecting the progress made by the drill bit. Thus, the weight on the bit may be maintained at a constant. Also, the neutral point within the drill string, namely that point at which there is neither compressive nor tensile stress, is localized within the joint. Thus, the tendency to disengage the coupling at or adjacent the neutral point may be overcome by use of right hand threads or the like.

It is obvious that the flow of lubricant past the spline engagement when the telescoping members change their relative axial positions is greatly restricted due to the close tolerance in the splined fitting. Thus, a dash-pot effect is obtained which serves to absorb or dampen vibrations and other shocks or jars occasioned by the action of the drill bit upon the formation, whipping of the drill stem and the like. In as much as the lubricant is forced into this space under pressure the space is completely filled and excessive hydrostatic pressures to which the outer member may be subjected are transposed to the inner member which is of heavier construction and is better able to withstand this pressure. In addition the lubricant increases the life of the tool both in its action as a lubricant and because of the shielding of the device from gritty or abrasive substances.

It will be seen that the objects of this invention have been accomplished. There has been provided a drill stem telescope joint capable of supplying a rigid connection for the transmission of torque which simultaneously permits extension of the joint as the drilling progresses. The arrangement is such that the working parts operate in a sealed chamber and are thus protected from abrasive material. The construction provides for an oil bath for the working parts of the tool, thus prolonging its life.

From the foregoing it will be seen that this invention is one well adapted to attain all of the ends and objects hereinabove set forth together with other advantages which are obvious and which are inherent to the structure.

It will be understood that certain features and sub-combinations are of utility and may be employed without reference to other features and subcombinations. This is contemplated by and is within the scope of the claims.

As many possible embodiments may be made of the invention without departing from the scope thereof it is to be understood that all matter herein set forth or shown in the accompanying drawings is to be interpreted as illustrative and not in a limiting sense.

Having described my invention, I claim:

1. A drill stem telescope joint including an outer tubular member, an inner tubular member adapted to telescope the outer member, a spline connection between the members, a sealing means at each end of the spline connection whereby said connection is protected from abrasive matter, said members telescoping each other beyond the spline connection with the inner member being of a reduced diameter beyond said connection, and

5 an auxiliary lip-type packing ring carried by the outer member and having its bore engaging the exterior surface of the reduced portion of the inner member, the exterior of the packing ring being exposed to the pressure of the fluid within the drill stem to which the joint is connected whereby said pressure fluid maintains the packing ring in sealing engagement with the inner member, the outer member below the packing ring having means for establishing communication between the area externally of said outer member and the bore of the packing ring, said ring allowing a by-pass of pressure in the event the pressure acting against its bore adjacent the inner member exceeds the pressure which is acting on its external surface.

2. A drill stem telescope joint including, an outer tubular member, an inner tubular member adapted to telescope the outer member, the upper 10 end of the outer member projecting beyond the upper end of said inner member, a spline connection between the members, a sealing means at each end of the spline connection between said members whereby said connection is protected from abrasive matter, a reduced diameter flow tube extending upwardly from the inner member and projecting axially through the outer member above the spline connection between the member, an annular packing element carried by the outer member and spaced above the upper end of the inner member, said element having an upwardly directed sealing lip engageable with the exterior surface of the flow tube for sealing off in a downward direction between the tube and the outer member to protect the sealing means at the ends of the spline connection, the exterior of said packing element being exposed to pressure fluid circulated downwardly into the outer member whereby such fluid maintains the packing element in sealing position, and means for establishing communication between the area exteriorly of the outer member and the annular space between the interior of the outer member and flow tube below the annular packing element, whereby pressure from exteriorly of the outer member may by-pass upwardly around the flow tube and past the annular packing element in the event that this pressure exceeds the fluid pressure acting on the exterior of the packing element.

3. A drill stem joint as set forth in claim 2, wherein the splines of the spline connection between the members are buttress splines.

4. A drill stem joint as set forth in claim 2, together with stop means separate from the splines of the spline connection for limiting the relative movement in both directions of the inner and outer members with respect to each other.
